CLAIM

The ornamental design for a bottle cap opener, as shown and described.

DESCRIPTION

FIG. 1 is a front perspective view of a bottle cap opener according to our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines showing portions of a bottle cap opener depict environment and form no part of the claim.

1 Claim, 5 Drawing Sheets(56)
